UNITED STATES PATENT OFFICE.

JOHN PETERSON AND FREDERICK OSCAR PETERSON, OF DETROIT, MICHIGAN.

EXPLOSION-ENGINE.

1,238,330.

Specification of Letters Patent. Patented Aug. 28, 1917.

Continuation of application Serial No. 681,178, filed March 2, 1912. This application filed October 7, 1915.
Serial No. 54,484.

To all whom it may concern:

Be it known that we, JOHN PETERSON and FREDERICK O. PETERSON, citizens of the United States, and residents of Detroit, in the county of Wayne and State of Michigan, have invented a new and Improved Explosion-Engine, of which the following is a specification.

This invention relates to means for supplying liquid fuel, such as gasolene, kerosene, alcohol or other hydro-carbons, in proper quantities to the explosion chamber of an internal combustion engine; and its object is to provide a simple and compact device which shall supply said fuel to the explosion chamber in proportion to the air at each operating stroke.

Our invention consists in combination with an internal combustion engine cylinder, of a casing having a compression chamber and an air passage connecting the inlet port and the compression chamber, a fuel chamber surrounding a portion of said passage, a float-valve in said fuel chamber to control the level of the fuel therein, and a nozzle connecting into said fuel chamber and into said air passage, through which nozzle the fuel may pass into the air passage at the beginning of each compression stroke of the piston. Our invention further consists in combination with the mechanism set forth, of an air-pipe whereby the pressure in the fuel chamber will normally equal that in the compression chamber. Our invention further consists in an automatic closing device operated by the fluids in the explosion chamber and in the compression chamber, whereby the flow of fuel from the nozzle will be permitted to occur at each alternate or at every fourth stroke of the piston at will. It further consists in controlling means whereby the cycle of strokes at which fuel is permitted to pass to the explosion chamber may be regulated.

In the accompanying drawings, Figure 1 is a vertical section of an internal combustion engine embodying this invention. Fig. 2 is a vertical section of the manually operated cycle-controlling valve. Fig. 3 is a plan of an engine of the type shown in vertical section in Fig. 6 embodying this invention. Fig. 4 is a section on the line 4—4 of Fig. 1. Fig. 5 is a vertical section of an engine embodying a slightly modified form of this in-

vention. Fig. 6 is a section similar to Fig. 1 of a modified form of this invention.

Similar reference characters refer to like parts throughout the several views.

In the accompanying drawings, and especially Fig. 1, 1 is a crank-case and 2 the cylinder of an internal combustion engine having a piston 3 and connecting rod 4. Surrounding the cylinder is a water-jacket 5, through which extends a threaded thimble 6 for the spark-plug. The usual exhaust ports 7 and passage 8 may be employed, while the air intake valve 9 of any desired construction is connected into the crank-case in any desired manner.

As is usual in engines of this construction, the crank-case constitutes a compression chamber, but this invention is not limited to engines in which the crank-case performs this office. The wall of the lower portion of the cylinder is formed with a passage 11 which constitutes a portion of the transfer passage, the remainder being formed in an auxiliary casting 12, constructed with a U-shaped air passage 13, the lower end of which connects with this passage 11 in the cylinder wall, and the upper portion connecting with the intake port 14 of the engine.

Surrounding this passage 13, as shown in Fig. 4, is a fuel chamber 15. A nozzle 16 is open at its lower end in the fuel chamber and has an upper discharge opening 17 within the air passage 13. A pin 18 extends through the walls of an extension 19 on the cap 20 of the fuel chamber and on it is pivoted a lever 21, to which is secured the horseshoe-shaped float-valve 22. The outer end of the lever 21 connects to a small arm 23 by means of a pin 24, the upper end of said arm 23 connecting to the ball-valve 25, which controls the flow of fuel into the fuel chamber. As the valve 25 is on the opposite side of the wall of the float chamber, the vacuum which occurs in the float chamber at each alternate stroke of the piston 3 will aid in holding this valve on its seat. A fuel passage 26 is provided with a valve-seat 27 for the ball valve 28, which acts as a check-valve and prevents the return flow of the fuel to the supply-pipe 30. The usual plugs 31 may be employed to give admission to the valves 24 and 28 and to their seats.

The upper wall 32 which separates the

fuel chamber and the passage 13, may be provided with a sleeve 33, in which is seated an air-tube 34, a cap 35 being provided to permit the insertion of this tube 34. The operation of the device up to this point is as follows. When the parts thus far described are in the position shown in Fig. 1, a few drops of fuel are flowing from the aperture 17 and vaporized, the vapor mixing with the air rushing up through the passages 11 and 13 and through the ports 14 into the explosion chamber or cylinder 2, where the carbureting is effected. The rising piston 3 immediately closes the port 14 and compresses the charge within the explosion chamber. Immediately after the first rush of air through the passages 11 and 13 has ceased, the pressure within the fuel chamber 15 and the passage 13 will balance by reason of the connection through the tube 34, and as the aperture 17 of the nozzle is just above the level of the fuel in the fuel chamber, no more fuel will flow from said aperture.

25 When the charge in the cylinder is exploded, the piston 3 will descend and compress the air in the crank-case, producing a pressure which is communicated to the air in the fuel chamber through the passages 30 11 and 13 and the tube 34. Just before the port 14 is uncovered by the piston, a considerable pressure exists in the fuel chamber. Immediately after the port 14 is uncovered, the air in the chamber 13 rushes through the port, and the pressure at the aperture 17 within this passage is reduced, and this reduction occurs a sufficient period of time prior to the reduction of the pressure in the fuel chamber, by reason of the rush of air therefrom through the pipe 34, that a few drops of fuel will be forced up the nozzle 16 and out of the aperture 17 by reason of the pressure in the fuel chamber being greater than at the aperture 17. The relative amount of fuel at each discharge is controlled by the small needle-valve 37, mounted in the casing 12, and having a pointed end at the discharge aperture 17.

50 The evaporation of the fuel at the aperture 17 will reduce the temperature within the passage 13 and prevent the fuel in the fuel chamber from over-heating.

It will be noticed that this fuel-feeder may be connected to any of the usual two-cycle engines by fitting the body of the feeder to the cylinder wall after cutting an opening into the transfer passage 11 and placing a barrier 32 therein.

60 The pressure of air in the crank-case 1 at the end of the explosion stroke, and therefore the pressure in the fuel chamber 15, will depend upon the amount of air which has entered the compression chamber through the valve 9. By adjusting the movement of this valve, the amount of air which enters

the crank-case at each compression stroke can be controlled and thus the difference between the pressure in the fuel chamber and at the aperture 17 at the instant the port 14 opens is also thereby controlled. We have found that this construction regulates the amount of fuel discharged at each opening of the port 14 from the orifice 17, which discharge is proportionate to the amount of air drawn into the crank-case at each up stroke of the piston 3.

70 It is well known that the horse-power of a two-cycle engine is greater than that of a four-cycle engine of the same weight, but that the fuel consumption per horse-power is usually also greater, due to the incomplete scavenging of the explosion chamber. The construction shown in Figs. 1 and 2, and shown in plan in Fig. 3, adapts this engine to operate on either the two-cycle or four-cycle principle. This is done by preventing the fuel from flowing from the aperture 17 at each alternate opening of the intake port 14.

75 Connecting into the wall of the cylinder 90 and communicating with the explosion chamber through a passage 40, is a valve 41 having a plug 42 provided with a handle 43. A pipe 44 extends to a small check-valve 45 having a ball-valve 46. A pipe 47 connects 95 to the head of a small cylinder 48, within which is a piston 49 connected to a rod 50. A small block 51 of asbestos or similar heat-resisting material is mounted in the end of this rod, so that when a pressure occurs at 100 the outer end of the cylinder 48, this small block 51 will be forced against the end of the nozzle 16 and close the aperture 17. A second pipe 53 connects into the outer head of this cylinder 48 and also connects into the cylinder 2, at such a point that it will be uncovered by the piston 3 at the time that the piston reaches the upper end of its stroke, but will be covered during most of the other time.

105 The operation of this device is as follows. When the valve-plug 42 is in the position shown in Fig. 2, the explosion chamber is in communication with the upper end of the small cylinder 48 during such time as the passage 40 is uncovered by the piston 3. It may be considered that Fig. 1 illustrates the position of the parts while the explosive charge is entering through the port 14 as before described. During this time the piston 49 will be at the upper end of its stroke, and the closure 51 will be spaced apart from the orifice 17 in the nozzle 16. The piston 49 and piston-rod 50 will remain in this position during the compression stroke of the piston 3, and during the larger portion of the working stroke. After the piston 3 has uncovered the opening 40 toward the end of the working stroke, the pressure in the cylinder 2 will be such that burnt gases will 110

115 120 125 130

rush through the passage 40, the valve 41, the pipes 44 and 47, into the cylinder 48 and force the piston 49, the piston-rod 50 and the closure 51 downward against the end of the 5 nozzle 16, and close the aperture 17. This occurs just before the port 14 is opened, so that when the air rushes from the crank-case through the passages 11 and 13 and the port 14, there will be no fuel flowing from the 10 aperture 17 and nothing but pure air will pass into the cylinder 2. The piston 3 then rises and compresses air in the cylinder 2, and at the end of its up stroke, it opens the lower end of the pipe 53.

15 During this up stroke of the piston 3, a partial vacuum occurs in the crank-case and will also occur in the pipe 53, which will result in the piston 49 moving outward. It will be observed that the inner end of the 20 cylinder 48 communicates with the outer air by means of a small passage 54. At the end of this second down-stroke of the piston 3, fresh air will again rush up through the passages 11 and 13, and through the port 14 into this cylinder, forcing out the air in said 25 cylinder which is partially mixed with burnt gases, and practically completing the scavenging of all the burnt gases. During this rush of air the aperture 17 is opened 30 and fuel will flow therefrom as has been before described. It will be apparent that when the valve-plug 42 is turned, and the passage of the burnt gases under pressure to the upper end of the cylinder 48 is cut off, 35 that the piston 49, the piston-rod 50 and the closure 51 will remain in their outer position because of the suction which regularly occurs through the pipe 53.

Where heavy oils are used as fuel, it is 40 desirable that the pressure in the fuel chamber shall exceed that in the passage 13 for a longer time than when mobile fuel is employed. To continue this pressure for a longer period of time, the pipe 34 is omitted 45 and the aperture through which it passes in the wall 32 is closed. A pipe 56, shown in Figs. 3 and 6, is connected to the cap 35 and to the crank-case at any desired point, and because of its length and smaller diameter, 50 the friction of the air therein will cause the retention of the excess pressure in the fuel chamber. It will be noted that a pipe 56 of smaller diameter will cause this pressure to be retained for a longer period of time than 55 where the pipe is larger in diameter. Where an engine of four-inch stroke is running eight hundred revolutions per minute, a port 14 remains open only about two-one-hundredths of a second during each revolution 60 of the shaft. It will be apparent, therefore, that the friction of the air in the pipe 56 is a controlling factor, and that with mobile liquids, very short pipes only can be used.

In Fig. 5, the construction of the engine, 65 including the piston and intake-valve 9, is

similar to that just described. The fuel-pipe 30, check-valve 27, the two plugs 31, the fuel-valve 25, the lever 21, the float 22, the nozzle 16 and its opening 17, and the needle-valve 37 are all of the same construction as 70 heretofore described. An air-pipe 55 is mounted in the wall 56 which separates the air-passage 57 from the fuel chamber 58. The cap 59 is of such size that the float 22 can be introduced so that the removable part 75 20 of Fig. 1 is unnecessary.

The construction shown in Fig. 5 is simply a two-cycle engine adapted for gasoline and alcohol, and because of the shortness of the pipe 55, is especially adapted for high-speed 80 engines in which the crank-case compression is high. Where the crank-case compression is low because of the large size of the crank-case, and the connecting passages, a short pipe 55 will not give the most satisfactory 85 results, but a longer pipe 34 or a pipe 56 will be found more desirable. However, where the compression chamber is so formed that the air rushes in through the passage 11 under high pressure, the short pipe 55 will be 90 most desirable. In this case as well as in the other two, the amount of fuel discharged from the aperture 17 will be in direct proportion to the amount of air passing up through the passages 11 and 57 into the explosion 95 chamber of the cylinder of the engine. In each case, the aperture 17 should be slightly above the fuel level in the fuel chamber, so that there will be no overflow or flooding.

100 It has been found that the pressure within the fuel chamber 15 is slightly above the static pressure in the passage 13 at the lower end of the pipe 34 when the port 14 is opened, in the construction shown in Fig. 1, 105 and that a similar condition exists in the structure shown in Fig. 5. It must therefore be assumed that the air rushing from the crank-case through the passages 13 and 57 is projected into said pipes 34 and 55 110 and causes a pressure in said reservoirs due to the inertia of the air, or at least retard the flow of air through said pipes from the reservoirs and thus cause the pressures therein to remain higher than the pressures 115 at the discharge ends of the fuel nozzles during a small fraction of a second. When an engine is running nine hundred revolutions per minute and the port 14 is open one-sixth of the time, the port is open only one-ninetieth of a second, so that the exact action is difficult to determine. In either case, the inertia of the air causes relative pressures in the fuel reservoirs.

120 During the compression stroke of the engine, a partial vacuum occurs in the passages 11, 12 and 57, and will therefore occur in the fuel chamber. If the fuel level is sufficiently low to permit the float to lift the valve 25 from its seat, this partial vacuum will cause 130

fuel to flow up through the pipe 30 and into the fuel chamber. It is apparent that the pipe 56 may be dispensed with and that the pipe 34 could be continued any desired distance in the passages 11 and 13 toward the crank-case.

The advantage derived from having the discharge opening 17 central of the fuel tank lies in the fact that the fuel will remain at practically the same level with reference to the opening 17, irrespective of the tilting of the vehicles or the rolling of the launches in which the engines are mounted. By having the opening 17 above the fuel level, no flow of fuel occurs except at the time the pressure within the fuel chamber is above the pressure in the air passage.

We claim:—

1. In an explosion engine, the combination of a cylinder and a piston therein, a crank-case, a casing connected to said cylinder, said cylinder and crank-case connected by an air passage passing through the casing, a fuel chamber connected to said casing and extending around the same, a fuel nozzle extending through the wall between the fuel chamber and the air passage and into said air passage and having its discharge opening central of the fuel chamber, and an air-pipe connecting into said fuel chamber and air passage whereby the air pressure in the fuel chamber will normally be that of the crank-case, the cylinder end of the air passage being so positioned as to be opened by the piston at the lower end of its stroke.

2. In an explosion engine, the combination of a cylinder and a piston therein, a crank-case, a casing connected to said cylinder, said cylinder and crank-case connected by an air passage passing through the casing, a fuel chamber connected to said casing and extending around the same, a fuel nozzle extending through the wall between the fuel chamber and the air passage and into said air passage, an air-pipe connecting into said fuel chamber and air passage whereby the air pressure in the fuel chamber will normally be that of the crank-case, the cylinder end of the air passage being so positioned as to be opened by the piston at the lower end of its stroke, and means for closing said fuel nozzle at the end of each alternate down-stroke of the piston.

3. In an explosion engine, the combination of a cylinder and a crank-case connected by an air passage, a fuel chamber adjacent said air passage, a float valve in said fuel chamber for controlling the level of the fuel, a fuel nozzle projecting through the wall between the air passage and fuel chamber and having a discharge aperture just above the level of the fuel in the fuel chamber, and an air-pipe extending from the fuel chamber into the air passage with the opening into the air passage opposed to the air

moving through the air passage to the cylinder so as to retard the reduction of pressure in the fuel chamber.

4. In an explosion engine, the combination of a cylinder and a crank-case connected by an air passage, a float valve in said fuel chamber for controlling the level of the fuel, a fuel nozzle projecting through the wall between the air passage and fuel chamber and having a discharge aperture just above the level of the fuel in the fuel chamber, an air-pipe extending from the air passage to the fuel chamber, a piston within the engine cylinder, and automatic means for closing said fuel nozzle at the end of each alternate down-stroke of the piston.

5. In a fuel feeder for explosion engines, the combination of a body comprising a fuel chamber and an air passage, said body so constructed that it may be connected to the cylinder wall of an explosion engine in such a manner that the air passage will form part of the transfer passage of said engine, a float-valve in said fuel chamber for maintaining a constant fuel level therein, a fuel nozzle projecting through the wall between the air passage and fuel chamber and having a discharge aperture just above the fuel level, and an air-pipe extending downwardly from the upper portion of the fuel chamber into said air passage through said wall between said chamber and passage.

6. In an explosion engine, the combination of a cylinder and a compression chamber, a fuel-feeder body attached to said cylinder and comprising a fuel chamber and an air passage forming a portion of the transfer passage between the compression chamber and cylinder, a fuel nozzle extending from the fuel chamber into said air passage, a slide member for closing said nozzle, and means operated by the fluids in the cylinder and compression chamber for actuating said slide member to permit flow of fuel from the nozzle at the end of each alternate down-stroke of the piston.

7. In an explosion engine, the combination of a cylinder and a compression chamber, a fuel-feeder attached to said cylinder, said compression chamber and fuel-feeder connecting to the cylinder by means of a transfer passage, a fuel nozzle extending from the fuel feeder into said transfer passage, a movable member mounted in said transfer passage for opening and closing said nozzle to permit or prevent the flow of fuel, and means to control said movable member so as to change the action of said engine to that of a two-cycle or four-cycle engine at will.

8. In an explosion engine, the combination of a cylinder, a piston therein, and a compression chamber, a fuel-feeder body attached to said cylinder and having a fuel

chamber and an air passage forming a portion of the transfer passage between the compression chamber and cylinder, a fuel nozzle extending from said fuel chamber 5 into said air passage and having an aperture at its outer end, a pipe connecting to the fuel chamber for communicating thereto the pressure in the compression chamber, a fuel control cylinder formed in said fuel 10 feeder, a piston therein, a rod connecting to said piston and carrying means for closing the discharge aperture of the fuel nozzle, and a plurality of pipes extending from said fuel-control cylinder to the engine cylinder 15 and to the compression chamber, the pressures in the engine cylinder and compression chamber causing the actuation of said fuel-controlling piston.

9. In an explosion engine, the combination of a cylinder and a compression chamber connected thereto by a transfer passage, a fuel chamber, a fuel nozzle extending therefrom into said transfer passage, fluid-operated means for opening and closing said 25 fuel nozzle to control the flow of fuel, pipes extending into said cylinder and compression chamber for the passage of fluid to operate the fuel controller, and a piston in said engine cylinder to control the flow of fluids 30 through said pipes.

10. In an internal combustion engine having a combustion chamber, means for compressing air, a by-pass leading from said means to the combustion chamber, means 35 for opening said by-pass to the combustion chamber to permit the passage of air impelled by its pressure, an inclosed reservoir for liquid fuel having a fuel conduit opening to the interior of the engine, and a passage 40 communicating with said reservoir above the liquid therein and opening into said by-pass so that the air passing in said by-pass shall be projected into said passage to cause a pressure in said reservoir due 45 to the inertia of the air.

11. In an internal combustion engine having a combustion chamber, means for compressing air, a by-pass leading from said means to the combustion chamber, means for 50 opening said by-pass to the combustion

chamber to permit the passage of air impelled by its pressure, an inclosed reservoir for liquid fuel having a fuel conduit opening to the interior of the engine, and a passage communicating with said reservoir 55 above the liquid therein and opening into said by-pass against the current of air passing therein and extending in the direction of the movement of said air whereby said air is projected into said passage and causes 60 a pressure in said reservoir due to the inertia of the air.

12. In an explosion engine, the combination of a cylinder and a crank-case connected by an air passage, a fuel chamber adjacent said air passage, a fuel nozzle extending from the fuel chamber into the air passage and having a discharge aperture just above the level of the fuel in the fuel chamber, and an air pipe communicating 70 with said fuel chamber above the fuel therein and extending into said air passage in the direction of the current of air passing therein whereby said air is projected into into said air pipe and causes a pressure in 75 the fuel chamber above that at the discharge aperture of the fuel nozzle.

13. In an explosion engine, the combination of a cylinder and a piston therein, a crank-case, a casing connected to said cylinder, said cylinder and crank-case connected by an air passage passing through the casing, a fuel chamber connected to said casing and extending around the same, a fuel nozzle extending through the wall between the fuel chamber and the air passage 85 and into said air passage and having its discharge opening central of the fuel chamber, and an air-pipe subjected to crank case pressure connecting into said fuel chamber 90 whereby the air pressure in the fuel chamber will normally be that of the crank-case, the cylinder end of the air passage to the crank case being so positioned as to be opened by the piston at the lower end of its stroke. 95

In testimony whereof we sign this specification.

JOHN PETERSON.
FREDERICK OSCAR PETERSON.
